UNITED STATES PATENT OFFICE

EUGENE L. BARNES, OF BUFFALO, NEW YORK

AUTOMATIC VALVE

Application filed July 24, 1926. Serial No. 124,618.

This invention relates to automatic valves especially designed for use in a circulatory refrigerating system to control the flow of liquid refrigerant from the high pressure side of a/the system to the low pressure side of the same system without allowing the passage of vapor refrigerant.

An object of my invention is to provide a valve which is automatically actuated by the intermittent inflow and outflow of a predetermined measure of the liquid passing through the valve—at an elevation above a trapped body of said liquid subject to evaporation.

Another object of this invention is to provide an automatic valve for refrigerating systems which is opened by an overbalancing inflow of liquid refrigerant thereinto and which gravitates to closed position incident to the outflow of such overbalance through the valve.

A further object is to provide an efficient control for the valve, positive in its action, and which is free of all external liquid influence tending to interfere with its automatic operation.

Other objects and advantages will be apparent from the following description of a typical embodiment of my invention, while the subjoined claims serve to define those features which are deemed novel in the art.

In the drawings:

Fig. I is a longitudinal view, partly in section, of my automatic valve; and,

Fig. II is a transverse section taken on the plane indicated by the arrowed lines II—II in Fig. I.

Referring more in detail to the drawings the automatic valve of my invention is enclosed in a chamber or boiler 3 conveniently of cylindrical form and having one end 4 permanently closed-in, while the other end is fitted with a removable head 5 secured thereto by screw studs 6 threaded into the chamber flange 7. Liquid refrigerant is conducted from any suitable source, by way of a connection 8, into an elongated cylindrical vessel 9 mounted in and secured to the removable head 5 and extending (as shown) sub-

stantially horizontally in the boiler chamber 3.

Passage of liquid refrigerant from the supply vessel or connection 9 into the chamber or boiler 3 for the purpose of evaporation—as well as to maintain a suitable normal liquid level in the latter—is controlled by a vertically movable valve device which is lowered by an inflow of the liquid refrigerant into the vessel 9, and raised by outflow of said refrigerant into the chamber or boiler 3. This valve device comprises a cylindrical gravity or balance receptacle 10 with both ends closed-in by caps 11, while it is fitted medially with an embracing yoke 12 having a boss 13 bored and screw-threaded to receive the removable orifice-valve or outlet member 14. The yoke 12 also embodies parallel tubular legs 15 slidable vertically upon guide rods 16 (one at either side of the receptacle 10) rigidly supported by a winged yoke or annulus 17 mounted around and securely attached to the vessel 9. The guide rods 16 may be drifted—or screw-threaded—into the wings or lugs 18 of the annulus 17.

Liquid refrigerant is fed from the elongated vessel 9 to the balance receptacle 10 through an upright supply tube 19 conveniently screwed into a correspondingly threaded aperture in the annulus 17 and vessel wall. This tube 19 is provided at its upper end with an adjustable stop 20 whereby the vertical rise of the balance receptacle 10 is limited. Said stop 20 also serves as a valve head for cooperating with the seat at the upper side of the outlet member 14.

Formed on the annulus 17 is an extension 21 having spaced lugs 22 between which is pivoted, at 23, a counterbalance comprising longitudinally directed lever or rod 24 provided at the end adjacent said pivot 23 with a forked portion 25. This forked portion 25 co-operates with opposed knife-edge fulcrums 26, on the parallel legs 15, in supporting the receptacle 10; whereas the outer end of the lever or rod 24 is upwardly deflected and fitted with a screw-collar counterweight 27, which, when once adjusted to slightly overbalance the receptacle 10, normally closes the valve 14 on its seat 20, and

requires no further attention or adjustments.

Outflow of liquid refrigerant from the balance receptacle 10 into the casing or boiler 3 is by way of the bore 28 of the valve 14; 5 said bore being slightly larger than the external diameter of the tube 19.

The liquid refrigerant intermittently fed into the casing or boiler 3 is therein vaporized and returned by way of a conduit 29 to the compressor or other means whereby it is 10 re-liquefied.

The operation of my automatic valve is as follows: Assuming that the casing or boiler 3 is filled with liquid refrigerant to the 15 requisite normal level and that the valve 14 is closed to its seat 20—as shown—under action of the counterweight 27; it will be understood that, the balance receptacle 10 is now gradually supplied with liquid refrigerant from the chamber 9 by way of the tube 19 until it overbalances the counterweight 27. Immediately such overbalance takes place, the valve 14 will recede from its seat 20, incident to the added liquid weight in receptacle 10, and lower the receptacle 10 vertically over the guide rods 16, whereupon such added liquid weight is discharged through the valve bore 28 into the casing or boiler 3 to re-establish the normal liquid level 25 30 therein depleted by evaporation. Concurrent with the outflow of liquid refrigerant from the balance receptacle 10, said receptacle is gradually returned to its seat under cushioning influence of the outflow and the 35 influence of the counterweight 27.

As the cycle of operations, just set forth, continues it will be seen that I am able to automatically maintain within reasonable limits a predetermined level of liquid refrigerant in the trap chamber or boiler 3 since the 40 amount of refrigerant in the closed system is constant. Furthermore attention is directed to the fact that the balance receptacle 10 is, at all times, above the liquid level in the 45 chamber or boiler 3; and that it is, in no way, actuated or influenced by the liquid refrigerant in chamber or boiler 3; hence the receptacle 10 is not a "float" device but constitutes a balance which actuates the vertically movable valve 14.

While I have shown a particular construction of my automatic valve, it is to be understood the details as to form and arrangement of the parts thereof are susceptible of modification within the scope of the claims.

Having thus described my invention, I claim:

1. The combination with a boiler chamber of a circulatory refrigerating system and a 60 liquid refrigerant supply connection extending horizontally in said chamber, of a gravity receptacle in said chamber above said connection receiving liquid refrigerant therefrom, and means extending upward from 65 said connection at either side of said recep-

tacle for guiding its up and down movements.

2. The combination with a boiler chamber of a circulatory refrigerating system and a liquid refrigerant supply connection extending horizontally in said chamber, of a gravity receptacle in said chamber above said connection receiving liquid refrigerant therefrom, means extending upward from said connection at either side thereof for guiding 75 the up and down movement of said receptacle, and a counterbalance for said receptacle fulcrumed on said connection and engaging the receptacle between its said guide means.

3. The combination with a boiler chamber 80 of a circulatory refrigerating system and a liquid refrigerant supply connection extending horizontally in said chamber, of a gravity receptacle in said chamber above said connection receiving liquid refrigerant therefrom, a yoke mounted around said connection with guide rods extending upward therefrom at either side of said receptacle, and a yoke around said receptacle provided with means for engaging said guide rods.

In testimony whereof, I have hereunto signed my name at Buffalo, New York, this 22nd day of July, 1926.

EUGENE L. BARNES.
